UNITED STATES PATENT OFFICE.

FRANK E. SMITH, OF TROY, NEW YORK, ASSIGNOR OF ONE-HALF TO E. AUGUSTUS DENNIN, OF TROY, NEW YORK.

STOPPING ATTACHMENT FOR PHONOGRAHS.

1,415,270.

Specification of Letters Patent. Patented May 9, 1922.

Application filed June 7, 1921. Serial No. 475,722.

To all whom it may concern:

Be it known that I, FRANK E. SMITH, a citizen of the United States, residing at Troy, in the county of Rensselaer and State 5 of New York, have invented new and useful Improvements in Stopping Attachments for Phonographs, of which the following is a specification.

Reference may be had to the accompanying drawings, and the reference characters marked thereon, which form a part of this specification. Similar characters refer to similar parts in the several figures therein.

This invention relates to means for automatically stopping the rotation of the turntable of a phonograph or the like at the end of the record-induced movement of the tone-arm of the instrument.

The principal object of the invention is 20 to quickly stop the rotation of the turntable upon completing the reproduction of the record without materially retarding the speed of the turntable during the reproduction of any part of the record.

25 Other objects will appear in connection with the following description.

Fig. 1 of the drawings is a top plan view of a phonograph partly broken away showing my improved stopping mechanism applied thereto with the tone-arm in intermediate position and indicating by dotted lines at the right-hand side of the figure the extreme and outward position of the tone-arm.

35 Fig. 2 is a similar view showing the position of the parts immediately at the end of the reproduction of the record and indicating by dotted lines the final braking movement of the tone-arm which is automatically caused by my stopping mechanism upon the release of the tone-arm from the control of the record groove.

Fig. 3 is a cross-section taken on the broken line 3—3 in Fig. 1 through the tone-arm and the bracket mounted thereon.

45 Fig. 4 is a vertical cross section taken on the broken line 4—4 in Fig. 1.

50 Fig. 5 is a vertical cross-section taken on the broken line 5—5 in Fig. 2, through the axis of the brake-lever.

Referring to the drawings wherein the invention is shown in preferred form, 1 is the top or body of a phonograph upon which is rotatively mounted the usual turntable, 2, 55 having a depending peripheral flange, 3.

The turntable has the usual spindle, 4, upon which is mounted the record, 5, to rotate with the turntable.

The instrument also has the usual goose-neck tone-arm, 6, upon the outer end of 60 which a sound-box, 7, is mounted in the usual manner, said sound-box carries the usual needle, 8, engageable with the groove in the record.

The parts above described are found in 65 the ordinary phonograph and further description thereof will be unnecessary.

In carrying out my invention in preferred form, I mount upon the top or body, 1, of the phonograph a bracket, 9, upon which is 70 pivotally mounted at 10, a brake-lever, 11, carrying a brake, 12, movable into and out of engagement with the flange, 3, of the turntable, 2.

The lever, 11, may be extended out from 75 beneath the turntable in the form of an operating handle, 13, if desired.

A link, 14, is pivotally connected at one end at 15 to the brake-lever, 11, and at its other end is pivotally connected at 16, with 80 a bracket, 17, carried by the tone-arm.

The pivotal connection, 16, is preferably formed by means of a hook upon the end of the link, 14, which is readily insertible in and removable from an aperture in the end 85 of the bracket, 17.

The bracket, 17, is in the form of a clip mounted upon the tone-arm, by means of a clamping screw, 18, as shown in Fig. 3, the bracket being adjustable longitudinally of 90 the tone-arm by loosening the screw, 18.

The bracket can thus be secured to the tone-arm at different distances from the axis of oscillation of the tone-arm, whereby the linear movement of the pivotal connection, 95 16, can be varied with respect to a given angular movement of the tone-arm.

The link, 14, is preferably formed of two members secured together by a screw-bolt-and-slot connection, as shown in Fig. 4, 100 whereby the link can be lengthened or shortened from time to time as may be found desirable.

The pivotal connection, 15, between the link, 14, and the brake-lever, 11, is preferably formed by means of a yoke or clip, 19, slidably adjustable longitudinally of the brake-lever and secured in adjusted position by means of the screw-bolt which forms the pivot. 105

- The brake-lever, 11, is thus actuated through the bracket, 17, and link, 14, by the swinging movements of the tone-arm; and the parts are so arranged that in either extreme position of the tone-arm the brake, 12, is forced into firm or braking engagement with the flange, 3, of the turntable, to stop the rotation of the turntable, as indicated by dotted lines in Fig. 2, and at the right-hand side of Fig. 1, while in intermediate position of the tone-arm the brake is withdrawn from braking engagement with the flange, 3, as shown by solid lines in Figs. 1 and 2.
- Movement of the tone-arm in one direction is induced by the engagement of the needle, 8, with the groove in the record, 5, in the usual manner, the return movement being accomplished by hand in the usual manner.
- A coil-spring, 20, which connects the brake-lever, 11, with a stud, 21, on the bracket, 9, tends to move the brake-lever, 11, in the same direction in which it is moved by the record-induced movement of the tone-arm.

The connection of the spring, 20, with the brake-lever is made by means of a screw, 22, by adjustment of which the tension of the spring can be regulated. The tension of the spring, 20, is thus regulated to such a degree that it is overcome by the engagement of the needle, 8, with the groove in the record.

The operation is as follows:

The tone-arm is withdrawn by hand in the usual manner to the position indicated by dotted lines at the right-hand side of Fig. 1, thus forcing the brake, 12, against the flange, 3, of the turntable to hold the turntable against rotation.

The desired record, 5, is applied to the turntable, the tone-arm is swung inwardly by hand to permit the turntable to rotate, and the needle is placed in the outer portion of the groove in the record.

The operation of the phonograph then proceeds in the usual manner, the tone-arm being gradually swung inward as the needle, 8, traverses the groove in the record. As the needle approaches the inner end of the groove in the record the movement transmitted from the tone-arm through the bracket, 17, and link, 14, to the brake-lever, 11, causes the brake, 12, to gradually approach the flange, 3, of the turntable until approximately at the time that the needle, 8, reaches the inner end of the groove in the record, the brake, 12, makes contact or is about to make contact with the flange, 3. As soon as the needle, 8, reaches the inner end of the groove in the record, the spring, 20, which is then released from the restraining influence which was due to the engagement of the needle with the groove, quickly swings the tone-arm from the position shown by

solid lines in Fig. 2, to the position indicated by dotted lines in that figure, thus completing the braking movement of the brake-lever, 11, and forcing the brake, 12, firmly against the flange, 3, of the turntable.

By properly regulating the tension of the spring, 22, the braking action of said spring can be prevented so long as the needle, 8, engages the groove in the record; while a quick swinging braking movement of the tone-arm will be caused by said spring as soon as the needle, 8, reaches the inner end of said groove.

By proper adjustment of the bracket, 17, the movement of the brake-lever, 11, can be so regulated that the brake, 12, will not effectively engage the flange, 3, of the turntable until just as the needle, 8, reaches the inner end of the groove in the record.

It is thus possible to effectively brake and stop the machine without any retarding action upon the turntable during the reproduction of the record.

What I claim as new and desire to secure by Letters Patent is—

1. In a phonograph-stopping mechanism, the combination with the tone-arm; and the record-supporting turntable; of a brake-lever; a link having one end pivotally connected with the tone-arm and the other end pivotally connected with the brake-lever; a brake carried by the brake-lever engageable with the turntable at the end of the record-induced movement of the tone-arm; and a spring tending to move the tone-arm in the same direction in which its movement is induced by the record.

2. In a phonograph-stopping mechanism, the combination with the tone-arm; and the record-supporting turntable; of a brake-lever; a link having one end pivotally connected with the tone-arm and the other end pivotally connected with the brake-lever; and a brake carried by said brake-lever engageable with the turntable in either extreme position of the tone-arm.

3. In a phonograph-stopping mechanism, the combination with the tone-arm; and the record-supporting turntable; of a brake-lever; a link having one end pivotally connected with the tone-arm and the other end pivotally connected with the brake-lever; a brake carried by said brake-lever engageable with the turntable in either extreme position of the tone-arm; and a spring tending to move the tone-arm in the same direction in which its movement is induced by the record.

4. In a phonograph-stopping mechanism, the combination with the tone-arm; and the record-supporting turntable; of a bracket adjustably mounted upon the tone-arm; means for securing said bracket in selected adjusted position; a brake-lever; a link having one end pivotally connected with said bracket and the other end pivotally con-

nected with the brake-lever; and a brake carried by said brake-lever engageable with the turntable at the end of the record-induced movement of the tone-arm.

5. In a phonograph-stopping mechanism, the combination with the tone-arm; and the record-supporting turntable; of a bracket adjustably mounted upon the tone-arm; means for securing said bracket in selected 10 adjusted position; a brake-lever; a link having one end pivotally connected with said

bracket and the other end pivotally connected with the brake-lever; a brake carried by said brake-lever engageable with the turntable at the end of the record-induced 15 movement of the tone-arm; and a spring tending to move the tone-arm in the same direction in which its movement is induced by the record.

In testimony whereof, I have hereunto set 20 my hand this 31st day of May, 1921.

FRANK E. SMITH.
